DESIGN FOR A DOLL

Jeanne Price and Thornton Hee, Van Nuys, Calif.

Application May 18, 1946, Serial No. 129,818

Term of patent 3½ years

(Cl. D34—4)

To all whom it may concern:

Be it known that we, Jeanne Price and Thornton Hee, citizens of the United States, residing at Van Nuys, county of Los Angeles, State of California, have invented a new, original, and ornamental Design for a Doll, of which the following is a specification, reference being had to the accompanying drawing, forming a part thereof.

We claim:

The ornamental design for a doll, as shown.

JEANNE PRICE,
THORNTON HEE.
